UNITED STATES PATENT OFFICE

GEORGE H. NOBBS, OF WATERTOWN, MASSACHUSETTS

SURFACING MACHINE

Application filed December 22, 1927. Serial No. 241,743.

My invention relates to surfacing machines generally, and particularly to machines for cleaning, polishing and otherwise operating upon floors, fixtures, furniture and the like, and it has for its object to provide an improved machine of this class.

Many attempts have heretofore been made to produce a practical electrically operated floor cleaning and polishing machine and some of these machines have been quite successful in eliminating the laborious work formerly required to clean and polish a floor by hand. Many of these machines, however, were so constructed as to apply too much pressure, or not enough pressure, upon the brush, pad or other tool to produce the desired result, particularly when giving the final luster that is desirable as a finish to a floor. In many of these machines this was due to the fact that the entire weight of the structure was sometimes carried by the brushes or pads and sometimes by rollers provided on the frame and resting on the floor. With the last mentioned type was present the objection that the brush or other tool would not properly follow inequalities or any unevenness in the floor. Furthermore, machines of the latter type were further objectionable for the reason that the wheels or rollers were liable to strike and mar or disfigure the wood-work. Machines of that type where the brush or other tool supported the whole weight were objectionable, also, for the reason that it was difficult to direct and control the same owing to the tendency of the rotating or otherwise movable brush or pad to shift the structure about.

My invention has for its object to provide an improved surfacing machine and particularly a machine of this class for use in cleaning or otherwise operating upon floors, fixtures, furniture and the like, which will be free and clear of the objections noted above and which will possess certain other advantages hereinafter pointed out.

To these ends I have provided an improved machine for operating upon floors, fixtures, furniture and the like, having the peculiar features of construction and mode of operation set forth in the following description,

the novel features of the invention being particularly pointed out and defined in the claims at the close thereof.

In the accompanying drawings:—

Figure 1 is a side elevation of a floor polishing machine constructed in accordance with my invention. 55

Figure 2 is a section on line 2—2 of Fig. 1.

Figure 3 is a central vertical sectional view of the lower portion of the machine shown in 60 Fig. 1.

Figure 4 is a bottom plan view of the parts shown in Fig. 3.

Figure 5 is a section on line 5—5 of Fig. 3.

Figure 6 is a sectional detail hereinafter 65 described.

Figure 7 illustrates a modification.

In the accompanying drawings, I have illustrated my invention as embodied in a machine for use in cleaning and polishing 70 floors or other flat surfaces, said machine including an annular ring-like metal base frame 1 having a vertical imperforate circular skirt portion 2 provided at its top with an inwardly extending flange or top wall portion 75 3 formed upon its upper side with a socket 4 within which is seated one end of the frame of a high speed universal electric motor 5 whose armature shaft 6 is disposed vertically as shown. Motor 5 is secured in place within 80 the socket 4 by means of screws 11.

Surrounding the lower end portion of the skirt 2, and abutting an annular rib or shoulder 2^a provided upon the exterior of the latter, is a felt ring 7 having its bottom side 85 formed with a plurality of radial air inlet conduit grooves 7^a which, in effect, divide the bottom portion of ring 7 into a circular series of floor engaging pads 7^b. This felt ring 7 is clamped or compressed on to the skirt 2 by a 90 ring-encircling sheet metal belt or strap 9 whose ends are fastened together by means of a bolt 10. Both the lower edge of belt 9 and the lower edge of skirt 2 are above the level of the air inlet conduit grooves 7^a as 95 shown clearly in Fig. 3 of the drawings. Thus the frame 1 is an inverted cup-like structure whose lower edge or chime is constituted by a felt member 7 herein shown as formed upon its bottom side with radial con- 100

duit grooves 7^a through which the interior of said frame communicates with the outside atmosphere. The top wall 3 of this inverted cup-like frame structure is made with a plurality of air outlet ports 3^a.

5 The shaft 6 of motor 5 projects downwardly into the chamber 12 provided by base frame 1 and has mounted thereon a sleeve 13 that is fixed rigidly thereto by a pin 14. Slidably 10 mounted upon sleeve 13 is a hub 15 that is splined to the sleeve by means of a pin 16 carried by said hub and extending through longitudinal slots formed in the sleeve, one of which is shown at 17. This hub 15 is made 15 near its upper end with an annular flange 18 to the under side of which is riveted a sheet metal plate or strip 19 formed at its middle with an aperture through which hub 15 extends. This plate 19 with its hub 15 constitutes the body portion of a fan or propeller 20 being provided at opposite sides thereof with obliquely disposed fan blades 20 which, when the shaft 6 is rotated in the direction of the arrow in Fig. 3, forces the air within base 1 25 upwardly into the upper part of chamber 12 whence it escapes through the ports 3^a. The relatively low air pressure thus established below the fan effects an inward flow of air through the conduit grooves 7^a. Thus, when 30 motor 5 is running currents of air are continuously flowing inwardly through said conduits and across the floor surface at the bottom of chamber 12.

The plate 19 is apertured to accommodate 35 screws 21 by means of which two bristle brushes 22 are secured to the under side thereof, at opposite sides of the hub 15. It will thus be clear that when the machine is in operation the reaction of the propeller or fan 40 constituted by the hub 15 and plate 19 with its wings 20, will thrust and hold the brushes 22 forcibly against the floor 23, and this utilization of the reaction thrust of the propeller or fan to forcibly, yet yieldingly, hold the brush 45 or other tool against the work independently of the weight of the machine is an important and distinguishing feature of my invention.

The top side of the wall 3 is formed with lugs 26, Figs. 1 and 2, to which is pivotally 50 connected, as by a bolt 27, the lower end of a handle bar 28, said lower end being constituted by two oppositely disposed strap iron arms 29 and 30. The top of the frame of motor 5 is made with an upstanding pair of lugs 55 31 embracing one end of a rigid metal strut 32 to which they are pivotally connected by a bolt 33. The opposite end of strut 32 occupies a position between the ends of a strap iron sleeve 34 mounted upon the handle bar 28, 60 said ends being pivotally connected with the strut 32 by means of a bolt 35 provided with a wing nut 36. When the nut 36 is loose the sleeve 34 can be slid lengthwise of the handle bar to adjust the angle and height of the free 65 end of the same. By screwing the nut 36 up

tight the sleeve 34 is clamped immovably to the handle bar and at the same time the ends of the sleeve are clamped against the opposite sides of the end of the strut 32.

The circuit of motor 5 includes wires 37 70 each permanently connected at one end with the motor 5 as usual. The opposite ends of the wires 37 are separably connected by a two-part connector 38 of usual construction with the lower ends of a pair of wires 39 which extend upwardly through a hole or groove provided in handle bar 28 to the upper end of the latter. The upper ends of these wires 39 are fastened to a double coupling terminal 40 of usual construction by means of which they may be connected with a current supply. In one of the wires 39 is arranged a push button switch 41 mounted on handle bar 28 and so long as the operator maintains finger pressure on the push button 42 of switch 41 the circuit of motor 5 is closed and the latter is operating. When the push button is released this switch automatically opens the circuit of motor 5.

The pin and slot connection 16 and 17 is 90 made so as to permit outward movement of the brushes and their fan holder into positions where the floor engaging ends of the bristles are well outside of the plane of the bottom side of the felt ring 7. Therefore, 95 when the machine is placed down on the floor for use the brush holding fan will be shoved back into the base 1 until the felt ring comes to rest upon the surface of the floor. Now, 100 when the motor 5 is started by closing the switch 41 the brushes 22 are rotated and at the same time the propeller or fan exerts a downward thrust on the brushes which holds them against the floor under pressure as they 105 rotate while, also, air is caused to circulate through the conduit grooves 7^a, the chamber 12 and ports 3^a as described above. While the motor is operating the machine is slid about over the floor by means of the handle bar so that the floor is acted upon by the felt pads 7^b as well as by the brushes. Thus when 110 a cleaning or polishing fluid or medium is first spread upon the floor and then the latter is treated by the machine, the felt pads serve to rub such fluid thoroughly into, and spread 115 it about evenly over, the floor in advance of the brushes regardless of the direction in which the machine is moved.

In polishing a floor the felt pads 7^b may be 120 applied to the floor with any desired pressure by bearing down on the handle bar, thus producing the degree of pressure and friction necessary to rub the polishing fluid into the floor and to warm or heat the wax ingredient of the fluid which is desirable in applying the latter. Meantime the brushes sweep over the surface of the floor with a relatively light glossing pressure while the air passing through the chamber 12 acts to dry the floor 125 130

at the bottom of the chamber and to cool the wax.

As will be clear, worn out brushes are readily removed and new ones substituted when necessary. Also, other tools than brushes may be used in lieu of the latter and other material than felt may be used for making the ring 7.

The above described cleaning and polishing machine is of simple and efficient construction and by providing the same with appropriate tools it may be used for a variety of purposes and for other purposes than merely cleaning and polishing. When used for a purpose that results in the production of dust as in surfacing wood or stone, it will be clear that the up draft of air passing through the chamber 12 will entrain and carry off with it whatever dust is produced, thereby keeping the floor clean so that the tools will act with the greatest efficiency. When thus employed it may sometimes be desirable to provide some means for collecting the dust that is carried off with the air such as a dust receptacle connected with the ports 3^a by a suitable conduit or conduits as in vacuum sweepers or cleaners as heretofore constructed.

The strut 32 in addition to serving the function of a strut to hold the handle bar 28 rigidly in position, also can be used as a handle when desired. That is, when operating upon stair treads, walls or the like the machine can be readily manipulated and maintained under full control by grasping the strut 32 with one hand and the handle bar with the other.

By removing the bolts 27 and 33 and separating the connector 38 the handle bar and strut can be removed from the apparatus when desired.

Fig. 6 is a sectional detail taken transversely through the axis of the member 16 except that the latter is shown in elevation and as shown in this figure the member or pin 16 is threaded at one end and screwed into a threaded hole provided in the hub 15. This construction permits of removal of the pin 16 and when the same is removed the tool carrying propeller fan can be slid off from the sleeve 13. With the instrument above described I propose to furnish more than one propeller fan carrying different kinds of tools and, as will be clear, this construction permits of removal of one propeller fan and the substitution of another.

In Fig. 7 I have shown a modified form of tool holder constructed also to serve as a fan or propeller wherein the plate 19 provides two diametrically opposite radial tool carrying arms each made at opposite sides thereof with veins 20, the vein 20 at one side being directed obliquely upward and the vein at the opposite side obliquely downward. This form of holder will have greater capac-

ity as an air propeller than the form shown in Figs. 3 and 4.

What I claim is:—

1. A machine of the character described comprising a base frame that is supported directly by the floor or the like; a motor mounted upon said frame; a rotary propeller fan splined upon the shaft of said motor; and a tool connected with said propeller fan and yieldingly held against the floor or the like by the reaction thrust of said propeller fan. 70

2. A machine of the character described constructed in accordance with claim 1 and wherein the propeller fan is separably splined to the shaft of said motor so as to provide for removal thereof and the substitution of another propeller fan. 75

3. A machine of the character described comprising an inverted cup-like base frame whose chime rests upon the floor or the like; an electric motor mounted centrally upon the top of said frame with its armature shaft in a vertical position and projecting into the interior of said base frame; a rotary propeller fan splined upon the shaft of said motor, and a tool carried by said propeller fan and yieldingly held against the floor or the like by the reaction thrust of said propeller fan. 85

4. A machine of the character described constructed in accordance with claim 5 and wherein the chime of said base frame consists of floor engaging pads that are separated to provide radial air conduit grooves between them and wherein said base frame is provided with an air outlet port. 90

5. A machine of the character described comprising a metal base frame annulus; floor engaging pads of felt carried by the lower portion of said base frame, and separated to provide radial air inlet passages between them; a motor centrally mounted upon the top of said frame with its armature shaft projecting within the latter; a rotary propeller fan splined upon the shaft of said motor; a tool carried by said propeller fan and yieldingly held against the floor or the like by the reaction thrust of said propeller fan, and an air outlet port at the top of said base frame annulus. 105

6. A machine of the character described comprising a metal base frame annulus having a skirt portion provided at its top with an inwardly extending top wall flange made with an air outlet port; a ring of felt or the like surrounding the lower portion of the skirt and projecting below the latter, said ring being formed at its bottom with a series of floor engaging pads that are separated to provide radial air conduit grooves between them; means fixedly clamping said ring in position on said skirt; a centrally disposed electric motor mounted upon and secured to the top wall flange of said base 110

frame with its armature shaft in a vertical position and projecting into said base frame; a rotary propeller fan within said base frame having a hub splined upon the shaft of said motor and a pair of radially disposed fan arms projecting from opposite sides of said hub and a tool separably but rigidly fastened to each arm and yieldingly held against the floor or the like by the reaction thrust of said fan arms.

7. A surfacing machine comprising a frame; a tool rotatably mounted on said frame and movable axially relatively thereto toward and from the work; a propeller fan connected with said tool so that its reaction thrust urges said tool toward the work, and means for rotating said tool and propeller fan.

8. A surfacing machine comprising a rotatably supported tool carrying member made with vanes and yieldingly urged toward the work by the reaction thrust of said vanes when the member is rotated; means for rotating said member and a frame by which said member is supported so as to be movable toward and from the work.

Signed by me at Boston, county of Suffolk and State of Massachusetts this 16th day of December, 1927.
